UNITED STATES PATENT OFFICE.

HARRY BLOUNT, OF OAK PARK, AND JOHN WAYLAND HERNLUND, OF GLEN ELLYN, ILLINOIS, ASSIGNEES TO WESTERN ELECTRIC COMPANY, INCORPORATED, OF NEW YORK, N. Y., A CORPORATION OF NEW YORK.

WIRE-DRAWING APPARATUS.

Application filed June 6, 1922. Serial No. 566,222.

This invention relates to wire drawing apparatus, and more particularly to a machine for stringing and positioning upon a rod or wire a series of dies preparatory to placing the rod or wire with the dies strung thereon in a wire drawing machine for drawing it down to its final size.

The object of the invention is to provide a machine of the above type whereby this stringing operation may be accurately and readily performed and with a minimum use of floor space.

In accordance with the general features of this invention there is provided a rotatable and a stationary drum both mounted about a common horizontal axis. The rotatable drum is adapted to pull the rod or wire through a succession of dies individually. The stationary drum serves as a storage for the wire as the dies are successively positioned thereon and also as a gauge for spacing the dies on the wire and is equipped with adjustable die stops to accommodate varying distances between dies. Means is provided for retaining the wire upon the stationary drum as each die is successively strung thereon. Clutch tripping means is also provided about which the wire is looped between the stationary drum and the die about to be positioned upon the wire, so that as the proper position of the die upon the wire is reached, the wire will be pulled tight on the stationary drum and also on the clutch tripping means thereby operating the clutch tripping means to stop the rotatable drum. Upon completion of the stringing operation the wire with the dies accurately strung thereon may be readily removed from the machine and upon stringing the wire drawing machine, each die will drop into its allotted position in the die holder.

In the drawings:

Fig. 1 is a front elevation of a die stringing machine embodying the features of the invention;

Fig. 2 is a side elevation thereof;

Fig. 3 is a plan section upon the line 3—3 of Fig. 2 with a portion in elevation;

Fig. 4 is an enlarged fragmentary view of a portion of Fig. 2 showing the clutch locking means in its unlocked position;

Fig. 5 is an enlarged fragmentary view partly in section of one of the adjustable die stops;

Fig. 6 is an enlarged fragmentary view of a portion of Fig. 1 showing the clutch locking means in its locked position;

Fig. 7 is a fragmentary detail plan view of Fig. 1 illustrating the groove formed in the drawing block for causing each succeeding turn of wire to clear the gripper;

Fig. 8 is a vertical sectional view through the rolls for pointing the end of the wire preparatory to stringing the dies thereon;

Figs. 9 and 10 are fragmentary front elevations of the machine showing several stages of the stringing operation, the wire being shown in exaggerated size, and

Fig. 11 shows the wire with the drawing dies strung thereon in the form in which it is removed from the machine, the wire being shown in exaggerated size.

Driving mechanism.

As shown in the drawings, the operating parts of the machine are carried upon a frame 10 provided with a base 11. Within the lower part of the frame 10 is housed a driving motor (not shown) which is connected to a driving shaft 12 carrying a sprocket 13. The sprocket 13 through a link chain 14 drives a sprocket 15 positioned at the upper part of the machine upon a shaft 16, which extends inward and carries intermediate its ends a worm 20 for driving a worm wheel 21, Fig. 2. The worm wheel 21 is mounted to turn freely upon a main shaft 22 to which is keyed a clutch 23 of the expanding ring type adapted to be driven by the worm wheel 21 when engaged therewith, Fig. 3. In the drawings the clutch and its operating means are shown in the positions they assume when the machine is operating. The clutch 23 is adapted to be engaged with the worm wheel 21 by a movement to the left (as viewed in Figs. 2 and 3) of a yoke member 24 about its pivot 25 in a well-known manner.

Drawing block and gripper.

Secured to the forward end of the shaft 22 is a drum or drawing block 28 carrying a suitable gripper 29 mounted in a pocket or depression 30 formed at the forward end and about the periphery thereof. A spiral semi-circular groove 27, Figs. 1 and 7, of suitable width is cut in the drawing block 28, starting at the gripper and continuing

for such a distance on a helix that will allow for the succeeding turns of wire clearing the gripper 29 as is usual in stringing machines. The gripper 29 is pivoted at 31 and in the rotation of the drawing block 28 it is limited in its movement about its pivot by stop pins 32 and 33 carried by the block 28. Mounted upon the frame 10 and about the shaft 22 is a wire storage and die spacing gauge drum 36 of the same diameter as the drawing block 28. The drum 36 is provided with a flange 37 which is secured to the frame 10, and formed in the flange is a circular T-shaped slot 38.

15 *Wire storage drum.*

The storage drum is provided with a suitable number of die stops 39, 39 seven of such stops being illustrated in the drawing. The die stops 39, 39 each comprise a supporting member 40, Fig. 5, adapted to be adjustably secured and positioned around the flange 37 of the drum 36 by a screw 41 threaded into a nut 42 slidably mounted in the T-shaped slot 38. Pivottally mounted upon the outer end of the supporting member 40 is a curved arm 43 which, when in use, projects forward and inward into engagement with the periphery of the drum 36, as clearly shown in Figs. 2 and 3. The free end of the arm is bifurcated, as indicated at 44, to allow the wire from the die being held thereby to pass therethrough and around the drum 36. The arm 43 is normally adapted to be held away from the periphery of the drum 36, as clearly indicated in Figs. 3 and 5 in dotted outline, by a coil spring 43' suitably mounted about the pivot of the arm 43 with one end of the spring resting against the arm 43 and the other end against the flange 37. In its normal position a lug 41' formed on the arm 43 rests against the flange 37 thereby limiting the movement of the arm 43 in a clockwise direction. When the arm 43 is to be used it is turned upon its pivot from the position indicated in dotted outline in Fig. 3 toward the axis of the drum 36 against the action of the spring 43' to the position shown in Figs. 2, 3 and 5 where it is locked from springing back by a trigger 45' provided with an operating handle 45. The trigger 45' is provided with a semi-circular surface 46' and the arm 43 with a co-operating similarly shaped surface 44', and when the surfaces 44' and 46' are in contact as indicated in Fig. 5 the arm 43 is locked from returning to its normal position. The trigger is turned by the operator in a counter clockwise direction by the handle 45 after moving the arm 43 into engagement with the periphery of the drum 36 whereupon the arm 43 is locked in position due to the co-operating surfaces on the arm 43 and trigger 45'. When it is desired to release the arm 43 from the trigger 45' to allow the

arm 43 to return to its normal position, the handle 45 is moved clockwise from the position shown in full lines in Figs. 3 and 5 to the position indicated in dotted outline in Fig. 5, whereupon the surface 46' thereon is moved away from the surface 44' upon the handle 43 and the spring 43' then functions to move the arm 43 about its pivot to the dotted outline position as shown in Figs. 3 and 5.

Pivottally secured to a bracket 48 secured to the face of the frame 10 and disposed parallel with the die stops 39, 39 is a spring actuated arm 49, Fig. 3, normally bearing against the periphery of the drum 36 adjacent its forward end. The arm 49 serves to hold the wire stored on the drum 36 from creeping onto the drawing block 28 during operation of the latter. A spring 50 holds the arm 49 against the drum 36.

A suitable brake 51 mounted upon the drawing block 28 and acting against the inner periphery of the stationary drum 36, Fig. 3, functions to check the rotation of the drawing block when the clutch 23 is disengaged. The action of the brake 51 is sufficiently light to allow a rotation of the drawing block by the operator when turning the block at the end of each stringing operation to bring the gripper 29 to its starting position, as shown in Fig. 1. For turning the drawing block by hand a handle 52 is provided which is mounted on the wire gripper.

A bracket 54 supports a die holder 55 which is adapted to swing about a pivot 56, Figs. 1 and 7, on a radius suitable for allowing several coils of wire as required to be distributed across the face of the drawing block 28.

A foot lever 57 (shown depressed) is adapted upon being depressed to actuate the clutch 23 for starting and stopping the drawing block 28. A spring 58, Fig. 2, acting on a system of levers connecting the foot lever 57 and the yoke member 24 functions to normally hold the clutch 23 from engagement with the worm wheel 21. Carried upon a stud 59 fixed to the front face of the frame 10 is a clutch tripping lever 62 provided with an upwardly projecting arm 63. In the operation of the machine, to be described later, the lever 62 is moved about its pivot stud 59 and toward the drum 36 to stop the operation of the drawing block 28. An arm 64, Fig. 1, on the lever 62 is secured by a pin and slot connection to a link member 65 provided intermediate its end with a cam face 68, Fig. 4. The lower end of link 65 is connected to a foot lever 69 a spring 70 being connected to the upper end of the said link to hold it in its normal position, as indicated in the drawings. Passing through a vertically disposed slot 71 formed in the link 65 and through the

cam face 68 is a turn buckle link 72 provided with ends rectangular shaped in cross section and provided with pins 73 and 74, Figs. 2 and 4. The pin 74 rests against the 5 cam face 68 when the machine is running, as shown in Fig. 1, and the pin 73 engages a slot 75 formed in the end of a bifurcated lever 76 secured to the yoke member 24 and movable therewith about the pivot 25 when 10 the foot treadle 57 is depressed to throw in the clutch 23.

Wire pointing mechanism.

A suitable mechanism for pointing the end 15 of the wire to be strung with dies as needed is carried on the frame 10 and is indicated at 81. The pointing mechanism consists of a series of pairs of grooved parallel steel rolls 82, 82, Figs. 1 and 8. Each pair of rolls 82, 20 82 is provided with a groove 79 in its periphery, which is of greater depth at one portion than the other as indicated at 80. Each pair of rolls is provided with a groove of different depth as clearly indicated in Fig. 1 to 25 provide for gradually reducing the size of the wire in the pointing operation. When the machine is in operation the rolls are continuously operated from the shaft 16 by suitable gearing (not shown) in the direction indicated by the arrows on Fig. 8. The operator, in using the pointing rolls, inserts a suitable length of the wire to be pointed between 30 the selected pair of rolls in a direction opposite to the rotation thereof, as shown in Fig. 35 8, and if the deep grooves 80 are positioned together as indicated in Fig. 8, the wire will enter therebetween and when the grooves of lesser depth come together they will compress the wire and cause it to move out from 40 between the rolls in a reduced or pointed condition.

Operation.

In the operation of the machine a sufficient 45 length of rod or wire is placed on the floor in the form of a long loop. The end 83 of the rod or wire is then inserted between a pair of the rolls 82, 82 of the pointing mechanism 81 to be reduced in diameter or pointed 50 for a sufficient distance from the end to receive the first die to be strung thereon. After placing the first die, indicated at 85, 55 on the wire, it is placed in the die holder 55 with the end of the wire projecting through the die far enough to be gripped by the gripper 29 mounted on the drawing block 28, Fig. 1. At this time the die stops 39, 39 are in the 60 position indicated in dotted outline in Figs. 3 and 5. The foot treadle 57 is then depressed from the dotted line position shown to the full line position to throw the clutch 23 into engagement. This movement of the treadle 57 rocks the yoke member 24 and the lever 76 in a counter-clockwise direction to 65 engage the clutch and move the turn buckle

link 72 to the right, as viewed in Fig. 4, thereby releasing the link 65 from the pin 74 which is being held by the top of the cam face 68, as shown in Fig. 4. The link 65 is moved up by the action of the spring 70 and 70 the cam face rides up with it and behind the pin 74, as shown in Fig. 2, thereby causing the lever 76 to be rocked to throw in the clutch 23 and holding it in engagement. The drawing block now starts to revolve and with 75 it the gripper 29, which pulls the rod or wire through the die 85 held in the die holder 55 until a specified predetermined number of turns of wire have been wound on the drawing block 28, Fig. 7, which will draw sufficient 80 wire through the die to provide for the succeeding reductions and proper locations of the other dies thereon, as shown in Fig. 11. The foot treadle 69 is depressed which moves the cam face 68 down to allow the link 85 72 to move to the left under the action of the spring 58, thereby disengaging the clutch 23 and stopping the drawing block. The wire wound on the drawing block is removed by the operator and the die 85 strung thereon is 90 placed behind the proper stop 39, as indicated in dotted outline in Fig. 2, and in full lines in Fig. 9, the stop 39 having been set in a predetermined position about the periphery 95 of the drum 36 as determined by the indices 100 on the flange 37. The arm 43 of the stop 39 with the die 85 therebehind is now moved downward by the operator to engage the periphery of the drum 36 as clearly shown in 100 Figs. 2 and 3.

After placing the die 85 behind the proper stop, a specified number of turns of the drawn wire are taken around the drum 36 by hand, Fig. 9, depending upon the distance to be maintained between the die 85 just strung and the following die 95, the wire being held on the drum 36 by the arm 49, and thereafter the wire is looped behind the arm 63 on the clutch tripping lever 62 as clearly shown in Fig. 9, the operator holding the coils 101 of the unstrung wire in his hand. The end 83 of the wire is pointed again, if necessary, and a second die 95 positioned thereon and placed in the holder 55 with the end of the wire gripped by the gripper 29 on the drawing block. The clutch is again engaged and the balance of the wire is pulled through the second die until all the slack is taken up and the wire becomes tight on the drum 36 with the second die properly positioned on the wire with respect to the first die. At this instant the clutch is disengaged by the pull on the arm 63 after all the slack in the wire is taken up. The movement of the arm 63 causes the disengagement of the clutch by moving the link 65 downward as is done by a depression of the foot treadle 69. After the second die 95 is properly positioned on the wire the handle 45 of the stop holding the first die 85 is 130

- operated and the arm 43 will move away from the periphery of the drum 36, as explained before, thereby permitting the coil of wire on the drum 36 and the first die positioned thereon to be slipped backward on the drum to be stored until all the dies are positioned on the wire. The second die 95 is now removed from the holder and positioned behind its corresponding stop 39, Fig. 10, after moving its arm 43 down against the periphery of the drum 36, and a specified number of turns of the drawn wire on the block 28 is slid back off the same and onto the storage drum 36, which operation is facilitated due to the fact that the block 28 and drum 36 are of the same diameter and in end to end engagement. The wire is then looped behind the arm 63 of the tripping lever 62.
- 20 The end 83 of the wire is pointed again if necessary and the third die 96, fourth die 97, etc., etc., are positioned thereon and placed in the holder and thereafter the same procedure is followed as has been described above until the proper number of dies which are to be used in reducing a given size rod or wire to a wire of required diameter, have been accurately positioned upon the wire.
- 25 The arm 49 is given a shape at the end which bears on the drum to allow the wire as it is coiled around the drum to slip under the arm against the action of its spring and thereafter to be held and prevented from creeping onto the drawing block.
- 30 Upon moving the arm 49 away from the drum the strung wire may be removed from the drum 36 and upon wrapping the wire around the capstans on the wire drawing machine the dies will drop into their proper holders.
- 35 What is claimed is:
1. In a machine for stringing dies upon wire, a drawing block, and a stationary wire storage drum positioned adjacent said drawing block whereby the wire may be transferred from and stored in close association with said drawing block as each die is strung upon the wire.
  2. In a machine for stringing dies upon wire, a drawing block, and a stationary wire storage means positioned about the axis of said drawing block whereby the wire may be transferred from and stored in close association with said drawing block as each die is strung upon the wire.
  3. In a machine for stringing dies upon wire, drawing means, and a stationary wire storage means positioned at the rear of said drawing means whereby the wire may be transferred from and stored in close association with said drawing means as each die is strung upon the wire.
  4. In a machine for stringing dies upon wire, a drawing block, and a stationary wire storage means positioned at the rear of said

wire drawing block in axial alinement therewith whereby the wire may be transferred from and stored in close association with said drawing block as each die is strung upon the wire.

5. In a machine for stringing dies upon wire, a drawing block, and a stationary storage drum so positioned that its entire surface is in peripheral alinement therewith whereby the wire may be transferred from and stored in close association with said drawing block as each die is strung upon the wire.

6. In a machine for stringing dies upon wire, a drawing block, and a stationary wire storage drum positioned at the rear of said drawing block and in peripheral and axial alinement therewith whereby the wire may be transferred from and stored in close association with said drawing block as each die is strung upon the wire.

7. In a machine for stringing dies upon wire, a rotatable drawing block, a wire storage device positioned at the rear thereof, and means associated with said device for preventing the wire from creeping onto the drawing block during operation thereof.

8. In a machine for stringing dies upon wire, a rotatable drawing block, a wire storage device positioned at the rear of the drawing block in axial alinement therewith, and means associated with said device for preventing the wire from creeping onto the drawing block during the operation thereof.

9. In a machine for stringing dies upon wire, drawing means, a wire storage device positioned adjacent said drawing block, and a pivotal spring pressed wire holding arm in engagement with said storage device for preventing the wire from creeping onto the drawing block during operation thereof.

10. In a machine for stringing dies upon wire, drawing means, and a gauge device about which the wire is coiled a specified number of times after each die is strung for spacing the following die on the wire, said device and drawing means positioned end to end.

11. In a machine for stringing dies upon wire, drawing means, and a gauge drum about which the wire is coiled a specified number of times after each die is strung for spacing the following die on the wire, said drum being provided with indices.

12. In a machine for stringing dies upon wire, a drawing block, a stationary drum about which the wire is coiled a specified number of times after each die is strung for spacing the following die on the wire, said drum having a plurality of indices, and said drum positioned at the rear of and in axial alinement with said drawing block.

13. In a machine for stringing dies upon wire, drawing means, a wire storage device adjacent thereto and a plurality of die stops associated with said device each adapted to

hold one of the dies during the stringing of the following die.

14. In a machine for stringing dies upon wire, drawing means, a wire storage device positioned adjacent thereto, and a plurality of adjustable die stops mounted adjacent the periphery of said device each adapted to hold one of the dies during the stringing of the following die.
- 10 15. In a machine for stringing dies upon wire, a rotatable drawing block, a stationary wire storage drum positioned adjacent thereto, and a plurality of adjustable die stops mounted about the periphery of said drum each adapted to hold one of the dies during the stringing of the following die, said storage drum having a plurality of indices for indicating the positions at which the adjustable die stops may be set.
- 15 20 16. In a machine for stringing dies upon wire, a power driven drawing block, a clutch therefor, a wire storage device positioned at the rear of said block, die holding means associated with said device and clutch releasing means about which the wire is looped between said block and die holding means and controlled by the tightening of the wire upon the device whereby the drawing block is stopped and when the die being strung is properly positioned upon the wire.
- 25 30

17. In a machine for stringing dies upon wire, power driven drawing means, a wire storage device positioned at the rear of said drawing means, means for stopping the operation of said drawing means, said stopping means including an element about which the wire is looped between the drawing means and the storage device and controlled by the tightening of the wire to stop the drawing means when the die being strung is properly positioned upon the wire. 40

18. In a machine for stringing dies upon wire, a power driven drawing block, a clutch therefor, a storage drum mounted adjacent the drawing block and about which the wire is coiled a specified number of times after each die is strung for spacing the following die upon the wire, a plurality of die stops mounted about the periphery of said drum each adapted to hold one of the dies during the stringing of the following die, and means associated with the wire between the drawing block and die stops and operable upon the tightening of the wire on the drum to cause the release of the clutch for stopping the drawing block. 45 50 55

In witness whereof, we hereunto subscribe our names this 31st day of May, A. D. 1922.

HARRY BLOUNT.
JOHN WAYLAND HERNLUND.
